JUSTIFICATION MEANS FOR TYPOGRAPHICAL MACHINES

Application filed August 31, 1929. Serial No. 389,767.

The present invention relates to typographical machines of the general class disclosed in Letters Patent of the U. S. No. 436,532 granted Sept. 16, 1890, to O. Mergenthaler wherein circulating matrices are released from a magazine and then composed in a line, the line transferred into a vertically movable "first elevator" or matrix supporting member which carries the line downward between two jaws which act as stops to fix the length of the line, after which the line is justified or expanded endwise by driving upwardly the spaceband wedges between the words, whereupon the line is presented before a mold which is then filled with molten metal to cast a type-bearing slug, the matrix line being thereafter carried away from the mold and the matrices returned through a distributing mechanism to their proper channels in the magazine.

In composing the matrices into lines in machines of this class, it is usual to use a spaceband or thin steel wedge between the words, and to effect justification of the line between the vise jaws before the cast takes place, the long wedges of the spacebands are driven upwardly by a justification bar so that all lines, regardless of whether they are exactly composed to the same length, will appear of the same length on the slug cast from the lines for the reason that the wedges of the spacebands will move upwardly when driven by the bar until the respective line becomes tightly spread out to exactly fill the space between the vise jaws which are previously set a predetermined distance apart.

The usual justification bar employed to drive the spacebands comprises a solid cross member carried pivotally on the upper ends of two stout rods, the power for driving the bar upwardly being applied to another solid cross member connecting together the stout rods at their lower ends. In that well known form of construction, a composed line of matrices and spacebands in which there are, for example ten spacebands will have the same total justification pressure applied to the spacebands as a similar line containing, for example, only two spacebands, so that a total force, eighty pounds for instance, will

result in eight pounds pressure applied to each spaceband wedge in the former line and forty pounds to each wedge in the latter line. In a line containing ten spacebands, however, the applied force of eight pounds per spaceband for justifying is only partially effective because of the friction between the spaceband wedge and sleeve members and in such a line, the total friction is obviously ten times that in a line having only one spaceband so that the total force applied must necessarily be quite large to overcome friction.

A line containing only one or two spacebands is therefore subjected to a much greater endwise expansion pressure when the spaceband wedges are driven up than a line containing a larger number of spacebands because the total friction between the wedge and sleeve of one or two spacebands is so small that a large part of the total applied pressure is effective in expanding the line. This excessive expansion pressure sometimes bends the spacebands and it also tends to spread the vise jaws between which the line is held as well as to spring the entire vise frame, and this results in variations in the length of the line of characters cast on the type bar. Such variations are common in printed matter, they being particularly noticeable in vertical rule or tabular matter wherein vertical rule lines comprise a series of short vertical lines which should butt together end to end without appearing staggered. This objectionable condition is well known in the printing art and many attempts have been made to correct it without success.

The object of the present invention is to provide a justification mechanism for machines of the class described for automatically applying approximately the same driving pressure on the wedges of the spacebands in a line regardless of whether few or many spacebands are present or of the positions the spacebands may occupy in the line.

A further object is to provide a justification mechanism wherein each spaceband in a line will be substantially independently justified and the pressure applied to drive the spaceband wedges will be entirely inde-

pendent of the pressure which actuates the justification mechanism.

With these and other objects in view, the invention consists of certain improvements and combinations and arrangements of parts as will be hereinafter described, various changes and alterations in the exact construction shown being contemplated and included within the scope of the appended claims.

10 In the accompanying drawings:

Fig. 1 represents a vertical section through the casting mechanism of a line casting machine embodying justification means constructed in accordance with the present invention;

15 Fig. 2 is a top plan view of the justification bar constructed in accordance with the present invention;

Fig. 3 is a rear perspective view of the improved justification means and the associated parts of the machine;

20 Fig. 4 is a diagrammatic view of the improved justification bar and a composed line of matrices, showing the manner in which the justification bar actuates the spacebands to 25 justify the line; and

Fig. 5 represents a vertical section through the justifying mechanism shown in Fig. 4, looking toward the left.

30 Similar parts are designated by the same reference characters in all of the figures.

The justification mechanism herein disclosed is applicable generally to typographical machines of the class wherein matrices and expansible spacebands or wedges stored in a magazine or other place of storage drop therefrom upon operation of delivery mechanism controlled by manipulation of the keys of a keyboard and the matrices and spacebands are carried to a common assembly point where they are stacked successively into a composed line which is transferred to the retaining rails or jaws of an elevator which carries the line down into position in front of a mold where the line is justified after which metal is injected into the mold to cast a type bar or slug against the line.

35 In the present instance, wherein the justifying mechanism is shown applied to a machine of the class illustrated and described in the patent hereinbefore referred to, 1 designates the usual vise frame carried on shaft 2 fixed in bearings on the forwardly extending arms 3 of the usual machine base 4, the metal pot 5 also being pivotally carried on the shaft 2 whereby the pot can advance for casting and retreat thereafter as the pot cam, not shown, rotates and transmits movement to the pot through the lever 6 in a manner well known in machines of this class. The 40 mold wheel 7 as usual is pivotally carried on an arm projecting from a so called mold slide so that any desired mold on the wheel may be set for casting type bars therein as molten metal is pumped from the pot, all of which

is well known to those skilled in the art so that details relating to their actions and which form no pertinent part of the invention are omitted from the drawings. 8 represents the usual spring which actuates the justification lever 9 pivoted on the machine frame by the shaft 10, this lever having an arm 9^a which carries a roller R which rides on the usual justification cam C.

In composing or assembling a line of matrices, it is customary, as is well known, to insert expansible spacebands, each comprising a sleeve and a vertically elongated wedge member slidably engaging it, between the words or wherever a space between characters is desired. A line may therefore comprise some ten or more spacebands or it may comprise only one or two, as for instance, in the case of a short line with only two words. In either case however, the justification mechanism heretofore used is such that the entire energy of the justification spring 8 acting upon justification lever 9 to drive it on its justifying stroke will be exerted in forcing the wedges of the spacebands upwardly to 90 expand the line to the full predetermined width between the usual vise jaws 11, 11^a, Fig. 4. One of the vise jaws, the so-called the constant jaw 11, is usually fixed and is supported against movement by the adjustable banking screw 12, while the jaw 11^a is movable so that it may be manually set to provide any desired spacing between the jaw faces between which the matrix line, also composed to a corresponding length, is positioned in the usual manner for justifying the line before the casting operation takes place. The application, however, of the full energy of the justifying spring 8 against only one or two spacebands results in an excessive expansion force which causes the vise jaws to spread and imposes an excessive driving pressure on the spacebands which often causes them to spring or bend.

As is well known to those skilled in the art and has been hereinbefore pointed out, the justification means heretofore used and employing a single or solid cross member to drive up all of the spacebands contained in the line is objectionable since the effective force applied to expand the line will be far less when the line contains a large number of spacebands than when the line contains a few spacebands and when a few spacebands are contained in the line the expansive pressure exerted thereby on the line is excessive. This excessive or varying justification pressure produces varying lengths of lines and this is particularly observed in lining up vertical rule or column matter as in tabular composition and printing.

To eliminate this objectionable condition, the solid justification bar usually employed is modified, according to the present invention, so that it comprises a series of independently

movable sections preferably in the form of flat rods 13, arranged to slide vertically in guideways formed in the top and bottom cross members 14, 14 rigidly secured to rods 15, 15 by pins. The rods 13 are held in their guides by plates 16, 16 secured to the cross members 14, 14 and are bent angularly at the top and bottom, the bottom being bent back under the bottom cross member 14 and then upward to form extensions which are provided with holes 17 into which springs 18 are hooked, the upper ends of the springs 18 being hooked into holes in the spring holding plate 19 secured to the back of the upper cross member 14.

The rods 15, 15, together with the cross members 14, 14 secured thereto, form a rigid frame which is mounted and guided for vertical movement in the usual lugs or extensions 20 at the bottom and mid-way up on the vise frame 1 and in which the vertical rods 15, 15 are slidable. The top ends of the rods 13 are bent back over the upper cross member 14 to provide areas of sufficient size to receive 25 the lower ends of the spaceband wedges, and are cut at an angle which deviates from a right angle to the length of the matrix line, as clearly shown in Fig. 2, so that a spaceband such as S', Fig. 2, which may fall at the junction of two of the bars 13 will have a firm seat on the top of both bars and not slip off as the justification pressure is applied and the bars 13 are driven upwardly. The lower plate 16 which is secured to the lower cross 30 member 14 and serves to retain the bars 13 in their lower guide, is provided with a shoe 21 which extends downwardly to align with and to be engaged at its under side by the front end of the usual justification lever 9.

In the operation of the machine, the composed matrix line containing matrices M and spacebands S is presented before a selected mold on the mold wheel 7, the composed line being retained as usual in grooves of the jaws 40 J of the first elevator E. The metal pot 5 is caused to advance in the usual manner to lock up against the back of the mold, and justification of the line then takes place through the rotation of the justification cam C which allows the spring 8 to impart motion to the usual justification lever 9, moving it in accordance with the profile of the cam under control of the roller R which is urged against the cam by the justification spring 8.

As the cam C revolves, the lever 9 moves upwardly under the force exerted by the spring 8, and the forward end of this lever contacts with the shoe 21 of the justification mechanism frame, causing the frame comprising guide rods 15, 15, cross members 14, 14, and justifier rods 13 with springs 18, to rise. The extent of upward movement of the frame produced by the upward stroke of the lever 9 will always be the same, but the individual justifier rods 13 will be obstructed

against full upward movement whenever the downwardly extending wedge members of the respective spacebands directly above them are struck. The springs 18 are of equal tension, and when the justifier bars 13 contact with the respective spaceband wedges, the corresponding springs 18 will expand as the frame continues to move upwardly under the influence of lever 9. Any of the bars 13 which do not meet a spaceband will remain seated against the bottom edge of the lower cross member 14 under the normal tension of their respective springs 18.

In Fig. 4, the justifying frame is shown after being raised by lever 9 from normal position represented by the dotted lines, to fully operated position represented by the full lines. The justifier bars 13, with the exception of the two marked *a*, have contacted with spacebands and have driven the wedges upwardly substantially equal distances, the driving force against each spaceband being about equal and determined by their respective springs 18 rather than by the driving force applied to the frame by the spring 8 and lever 9.

From the foregoing, it will be apparent that the usual justification spring 8 need only be strong enough to lift the justification mechanism frame and overcome the combined tension of the springs 18 when the latter are expanded to the maximum, that is, when a tight or very full composed line is being justified, under which condition the spaceband wedges can only be driven up to a small extent because the line is composed full enough to approximately fill out the set space between the vise jaws. It will also be apparent that each spaceband is subjected to an equal and individual driving force for moving the respective wedge and overcoming friction between the wedge and sleeve members, so that whether one or several spacebands are present in the line, an equal pressure will be applied to each for driving the wedge. Moreover, the total pressure acting to expand the line between the vise jaws will not exceed the sum of the pressures resulting from the individual springs 18, which is not great enough to cause undue strain and spreading of the vise jaws.

As already pointed out, a line comprising ten spacebands acted upon in the usual manner by a single or solid justification bar under the influence of eighty pounds would result in a force of approximately eight pounds per spaceband so that the springs 18 for the construction herein described may be selected which will produce a pressure of about eight pounds each when expanded to a point where the tops of the bars 13 contact with the spaceband wedges.

I claim as my invention:—

1. In a typographical machine having means for supporting a composed line of

matrices and expandible spacebands, justifying means comprising a frame having cross members at its ends and guided to move toward said line, means for moving said frame in said direction, a plurality of relatively flat justifying members extending longitudinally of said direction of movement of said frame and arranged in a row edgewise to each other at one side of said cross members and guided thereon to move independently in said direction, said justifying members having portions thereon beyond one of said cross members bent transversely toward the other side of the frame to independently engage different spacebands in the line and having portions thereon beyond the other cross member bent transversely toward said other side of the frame, and means interposed between said frame and the latter transversely bent portions on said justifying members and acting to force said justifying members independently against different spacebands in the line to expand them.

2. In a typographical machine having means for supporting a composed line of matrices and expandible spacebands, justifying means comprising a plurality of justifying members having means for guiding them to move independently, one beside another, and for bringing them into engagement with the spacebands in the line, adjoining sides of said members extending at an angle which deviates from a right angle to the length of the line, and means for forcing said members against the spacebands in the line to expand them.

3. In a typographical machine having means for supporting a composed line of matrices and expandible spacebands, justifying means comprising a frame having means guiding it to move toward the line, a row of justifying members carried by said frame and guided to move independently in the direction of movement thereof, said members having portions thereon beyond one end of the frame to engage the different spacebands in the line and having transversely extending portions thereon beyond the other end of the frame, and tension springs connected to said frame toward the spaceband engaging ends of the justifying members and to said transversely extending portions of the respective justifying members and acting on the latter to force them independently against the spacebands in the line to expand them.

4. In a typographical machine having means for supporting a composed line of matrices and expandible spacebands, justifying means comprising a frame embodying spaced cross members and guided to move toward and from the line, means to act on said frame and move it toward the line, a row of rods mounted side by side in said frame and guided to move independently in

the direction of movement of the frame, said rods at one end being bent to engage the spacebands in the line and being bent at their opposite ends to engage the frame and thereby limit the movement of said rods toward the line, and springs individual to said rods and acting to move them independently in a direction to expand the spacebands in the line.

In testimony whereof I have hereunto set my hand.

SAMUEL E. SPERRY.
